UNITED STATES PATENT OFFICE.

NICHOLAS S. VEDDER AND FRANCIS RITCHIE, OF TROY, AND TOBIAS S. HEISTER, OF LANSINGBURG, NEW YORK, ASSIGNORS TO JOSEPH BELL & CO., OF WHEELING, WEST VIRGINIA.

DESIGN FOR COOKING-STOVE.

Specification forming part of Design No. 7,955, dated December 22, 1874; application filed December 14, 1874.
 [Term of Patent 7 years.]

To all whom it may concern:

Be it known that we, NICHOLAS S. VEDDER and FRANCIS RITCHIE, of the city of Troy, in the county of Rensselaer and State of New York, and TOBIAS S. HEISTER, of the village of Lansingburg, in said county and State, have jointly invented and produced a new and original Design for Cooking-Stoves, of which the following is a specification, reference being had to the accompanying photograph of a cooking-stove having our said new design.

One part of this invention consists of the design for the panel ornament A, composed of the curved and inclined open scroll-tablet b, with folds c c' therein, and having a raised border, d, along each side, with scalloped edges e, and central projecting ornaments f, and forked ornamented ends g g', all shaped and disposed so as to appear substantially as shown in the aforesaid photographic representation.

Another part consists of the design for the large oven-door, as composed of the compound panel ornament A, the plain panel-surface H, and the panel-border I, composed of the outer convex molding j, the inner series of ornamentation k, and the intermediate molding l, each shaped and all arranged together so as to appear substantially as represented in the aforesaid photograph.

Another part consists of the design for the compound panel or leg ornament M, composed of the central raised shield-like tablet n, the arched top scroll o, the side scrolls p p', and the bottom scroll q, with the rosette r beneath, all shaped and arranged together so as to appear as represented in the accompanying photograph.

Another part consists of the design for the end fire-door or panel S, as composed of its rectangular form, the outer broad convex molding j, the inner molding l, the inside series of ornamentation k, composed of different alternating forms, shaped as shown, the plain surface t, and the compound central ornament M, composed of the shield-like tablet n, surrounded by the top, side, and bottom scrolls o, p p', and q, and rosette r, and the whole shaped and combined so as to appear as represented in the photograph aforesaid.

Another part consists of the design for the warming-closet door U, as composed of its rectangular form, the central compound ornament M, plain surface v, series of border ornamentations k, convex molding w, concave molding x, and flat outside fillet y, all shaped and arranged together substantially as represented in the aforesaid photograph.

Another part consists of the design for the end panel Z of the water-reservoir casing, as distinguished by having straight sides and bottom, and being narrower at the bottom than at the top, the central compound ornament M, the plain surface a, the series of ornamentations k, and the bead-molding h, all shaped and arranged together as shown in the aforesaid photograph.

Another part consists of the design for the upper front plate, as composed of the flat and convex outer molding B, the depressed flat surface C, the raised oblong rectangular panel-molding D, series of ornamentations k, and inner plain surface E, all shaped and arranged together on each of the two end portions of the said upper front plate, as shown and indicated in the aforesaid photograph.

Another part consists of the design for the front fire-doors, as composed of the oblong rectangular tablets F F, extended horizontally upon the lower parts, and having the series of ornamentations k k along the bottom and ends only, the rows of oblong rectangular register-openings G G, with projecting edges and ornaments J along the outer top and sides only, and the broad outside surrounding convex moldings j and inner concave moldings l, all shaped, proportioned, and arranged together as shown in the aforesaid photograph.

Another part consists of the design for the lower front plate K, as composed of the oblong rectangular tablet L, surrounded by the series of ornamentations k and outer panel-molding N, all shaped and arranged together and disposed upon the flat surface of the plate so as to appear as represented in the aforesaid photograph.

Another part consists of the design for the leg P, as composed of the compound ornament M, composed as above specified, and arranged

on the convex surface R of the leg, with the compound scroll ornaments T T' along the sides, and all shaped and arranged together so as to appear substantially as shown in the accompanying photographic representation.

We do not herein claim the design of the series of border ornamental k, nor the design of the panel-border I, composed of the convex molding j, series of ornamental k, and intermediate molding l.

What we claim as new and of our invention is—

1. The design of the panel ornament A, composed of the scroll-tablet b, with folds c c' therein, and raised border d, with scalloped edges e, projecting ornaments f, and ornamented forked ends g g', all shaped and arranged together as shown and described.

2. The design for the large oven-door, consisting of the compound ornament A, formed as above specified, the plain surface H, and the panel-border I, composed of the outer convex molding j, the series of inner ornamental k, and the intervening molding l, all shaped and disposed as shown and described.

3. The design for the compound ornament M, composed of the central raised tablet n, top scroll o, side scrolls p p', bottom scroll q, and rosette r, all shaped and arranged together as described and shown.

4. The design for the end fire-door or panel S, consisting of its rectangular form, the border composed of the moldings q and l, and ornamental k, the plain surface t, and the compound central ornament M, all shaped and arranged together as specified and shown.

5. The design for the warming-closet door U, consisting of its rectangular form, in com-

bination with the central compound ornament M, plain surface v, series of ornamental k, convex molding w, concave molding x, and outside fillet y, all shaped and arranged as shown.

6. The design for the end panel Z, having straight sides and narrowest at the bottom, with the ornament M, smooth surface a, series of ornamental k, and bead-molding h, all shaped and arranged as specified and shown.

7. The design for the upper front plate, consisting of the outer molding B, depressed surface C, panel-molding D, series of ornamental k, and plain inner surface E, all shaped and combined as shown and described.

8. The design for the front fire-doors, consisting of the oblong tablets F, with the ornamental k along the bottom and sides only, the register-openings G, with ornaments J along only the top and sides, and the surrounding broad convex molding j and inner concave molding l, all shaped and arranged together as shown.

9. The design for the lower front plate K, consisting of the tablet L, border ornamental k, and molding N, all shaped and disposed as shown and described.

10. The design for the legs, as composed of the compound ornament M, convex surface R, and scroll ornaments T T', all shaped and arranged as shown.

In testimony whereof we herenunto subscribe our names this 1st day of December, 1874.

NICHOLAS S. VEDDER.
FRANCIS RITCHIE.
TOBIAS S. HEISTER.
